U.S. Cl. D15—3

FIG. 1

FIG. 3

FIG. 1 is a perspective front view of the examination table embodying my new design, including an animal figure in upright position;

FIG. 2 is a side-elevational view thereof;

FIG. 3 is a top view, with the animal figure in the upright position of FIGS. 1 and 2; and

FIG. 4 is a view similar to FIG. 2 but with the animal figure in a bent-over position.

The stippling shown on the front of the article indicates the use of color or color contrasts.

I claim:

The ornamental design for an examination table, as shown and described.
